[57] **CLAIM**

The ornamental design for a building entrance, as shown and described.

DESCRIPTION

FIG. 1 is a perspective view of the building entrance showing the new design;

FIG. 2 is a front plan view of the present invention;

FIG. 3 is a first side view of present invention;

FIG. 4 is a rear view of the present invention;

FIG. 5 is a second side view of the present invention; and,

FIG. 6 is a top plan view of the present invention.

The broken line showing of environment in FIGS. 7-12 is for illustrative purposes only and forms no part of the claimed design.

FIG. 1

FIG. 6
